UNITED STATES PATENT OFFICE.

DANIEL W. SHIEK, OF CHICAGO, ILLINOIS.

TABULATING ATTACHMENT FOR COMPUTING-MACHINES AND THE LIKE.

No. 868,709.

Specification of Letters Patent.

Patented Oct. 22, 1907.

Application filed March 1, 1905. Serial No. 247,847.

To all whom it may concern:

Be it known that I, DANIEL W. SHIEK, a citizen of the United States, residing at Chicago, county of Cook, and State of Illinois, have invented certain new and 5 useful Improvements in Tabulating Attachments for Computing-Machines and the Like, of which the following is a description.

My invention relates to mechanism adapted to be attached to computing machines or similar devices 10 whereby the characters printed by the same may be conveniently arranged in lines, with the characters in the several lines arranged in rows or columns at substantially right angles to the general direction of the lines.

15 The object of my invention is to produce a simple, convenient, and effective device of the kind described, having a wide range of adjustment and one which may be quickly and positively manipulated to maintain the line or horizontal spacing to produce the desired 20 columns, or vertical alinement of the groups of figures or characters.

To this end my invention consists in the novel construction, arrangement, and combination of parts herein shown and described and more particularly 25 pointed out in the claims.

In the accompanying drawings wherein like or similar reference characters indicate like or corresponding parts, Figure 1 is an elevation of a portion of a computing machine equipped with my device, a portion 30 of the platen roller being broken away to more clearly show my device. Fig. 2 is a view of the tabulating mechanism and rack bar in their coöperating position showing the tabulating attachment secured to the frame of the machine. Fig. 3 is a view of the mechanism shown in Fig. 2 as seen from above. Fig. 4 is a section taken substantially on line 4—4 of Fig. 3. Fig. 5 is a section taken substantially on line 5—5 of Fig. 2. Fig. 6 is a section taken substantially on line 6—6 of Fig. 1. Fig. 7 is a view similar to Fig. 2 but showing the tabulating attachment secured to the carriage and the rack bar secured to the frame of the machine. Fig. 8 is a section taken substantially on line 8—8 of Fig. 7. Fig. 9 shows a modified form of part of the mechanism shown in Fig. 4, and Figs. 10, 45 11, 12, 13 and 14, illustrate various groupings of figures which may be secured with my improvement.

As shown in the drawings, 1, 1, Fig. 1 represents the carriage frames of the machine which support the platen roller 2. This platen roller may be of any construction suitable for the purpose and is provided with milled wheels 3—3 for effecting the rotary movement of the same by hand. At the rear of the machine and secured to the carriage frame thereof is a rack-bar 4 of the usual construction in machines of this kind. 50 Secured to the fixed frame of the machine is my tabulating attachment. Obviously however, the position

of these parts may be reversed if desired with the rack-bar secured to the fixed frame and the tabulating attachment secured to the carriage frame of the machine as shown in Fig. 7.

60

My tabulating attachment consists of an outer plate 5 provided with a finger piece 6, and coöperating mechanism to be hereafter described. One side of this plate is extended longitudinally of the rack-bar and is secured to the fixed frame as in Figs. 2 and 4 65 (or to the carriage frame of the machine as in Fig. 7). This longitudinal extension 9 is provided with an upright 10. An inner plate 11 of the same general outline as the circular portion of the outer plate 5 is secured to the terminal key piece 11^a of a revoluble 70 spindle 12 which passes through a circular opening in the outer plate 5 and is rotated at will by means of milled wheel 12^a. This inner plate 11 is notched at intervals upon its periphery, as at 13, for a purpose hereafter described. Pivotedly secured to the inner 75 plate 11 are a series of spacing wheels 14 of different diameters, and coinciding in number with said notches. In Fig. 4 I have shown the toothed wheels mutilated upon one side only, while in Fig. 9 I have shown them provided with teeth at regular intervals around 80 the circumference and delay surfaces between. Either form will operate satisfactorily in the use of the attachment.

Secured to the upright 10 at the points 15 and 16 are a pair of bell crank levers 17 and 18. The short 85 arms of the bell crank levers are united at 19 by a pin and slot connection or equivalent means. Upon the free end of lever 18 is a pin or projection 20 which fits into the notches 13 upon the periphery of the inner plate 11 and determines the engagement of the corresponding spacing wheel with the rack. These bell crank levers 17 and 18 are provided with a spring 21 at the pivot point of the lever 18 to the upright 10, of sufficient resiliency to maintain them in the position in which pin 20 is engaged with a notch, and the spring 90 22 coiled about the pivot of lever 17 and seated at one end in the frame bar 22^a, and at the other end against a pin from the heel end 22^b of the plate 5, acts upon the latter and the mechanism supported by it to carry it resiliently towards the rack so that said mechanism 95 may be raised out of engagement with the rack at any time to allow the spacing wheels to be moved over the teeth of the rack bar when the position of the tabulator is changed.

As above described my tabulating attachment is 105 secured either to the stationary frame of the machine or to the carriage in such position that the mutilated portion or delay surface of the spacing wheel in use at any time is upon the teeth of the rack bar with the first tooth upon either side of said delay surface engaging the teeth of the rack bar corresponding therewith, as shown in Fig. 4.

It will be observed that the wheels are of different sizes to be used in varying the spaces between the columns. These wheels may for convenience be numbered. An opening 23 may be provided in the outer plate 5 past which opening the wheels revolve, a number upon the plate 11 showing through the opening and indicating the spacing wheel in use.

In Fig. 4 I have shown the tabulator set for use with the medium wheel in position for operation. The operation is as follows: A sheet of paper is first placed beneath the platen roller, and after determining the number of columns of figures to be printed, and the space desired between said columns, the operator adjusts the tabulator so that the delay surface of the proper wheel 14 rests upon the rack 4, and moves the carriage to the desired position, *i. e.*, a position in which the type will register with the desired position of the right-hand or the left-hand column of figures. The first number to be printed is now set up in the machine, and the operator, by means of the keys (not shown) causes that number to be printed upon the paper in the desired position.

The computing machine contains nine (more or less) type carriers arranged in a horizontal row; so that any ordinary number, and therefore a whole column of numbers, may be printed without moving the paper-carriage longitudinally. The platen roller of the carriage is of course rotated a certain distance, after the printing of each number, by certain mechanism (not shown) belonging to the computing machine, which mechanism has no relation to any longitudinal movement of the carriage.

When the first column of figures is completed, the operator manually shifts the carriage to the right or the left (as the case may be) until the wheel 14 which engages the rack makes a revolution and its delay surface comes again into contact with the rack; and said wheel being spring-pressed against the rack, as hereinbefore described, the movement of the carriage 40 meets a sudden added resistance, by which the operator is notified that the carriage is in proper position for the next column of figures.

In case that spacing-wheels such as are shown in Fig. 9 are employed, the operation is the same, excepting that these wheels would stop five times during a revolution thereof.

To make the operation of this tabulating attachment more clear I will follow the operation of printing three columns of figures, taking for example those shown in Fig. 10. Supposing that the operator desires to print the left hand column first; after adjusting the tabulator for the purpose of engaging the proper spacing-wheel with the rack, the operator brings the platen-roller and carriage into position for printing the first number, 467899. This being printed without any movement of the carriage (as already explained) the operator causes the platen-roller to turn, by operating independent mechanism (not shown). Then the next number, 987654, is printed, and the last number, in that column, 322339. The operator now shifts the carriage to the right, and the carriage will be arrested by the action of the spring-pressed spacing-wheel. The operator turns the platen roller back to its initial position, and the first number (965432) of the second column is printed followed by

the others, as shown. The shifting of the carriage for the third column is identical with the shifting for the second column, as described.

If it is desired to use an index number after a large number, the form shown in Fig. 9 is particularly adapted for such purpose. For instance, 1,374,240—24, he will adjust his machine for vertical alinement at the units side of the column as before, set up the large number and print it, then by hand move the carriage one or two notches, (the click of the delay gear as it passes over the bar notifying him of the number of spaces or notches traversed) then set up the index number and depress the operating lever as before.

Whenever it is desired to increase or diminish the space between different groupings or columns to be added, the operator changes the wheel in engagement with the teeth of the rack bar by pressing with the thumb and finger, lever 17 towards finger piece 6, which operation will, through pin and slot connection 19, elevate the pin or projection 20 out of the notch 13, and then the operator, by turning spindle 12, brings into position the next gear desired for use, either the larger or smaller one, when lever 17 is released, and the pin 20 is allowed to drop into the notch directly above the wheel then in engagement with the rack bar, and the machine is now ready to adjust the vertical alinement of another column of figures.

I do not desire to limit myself to the exact construction of the tabulating attachment described nor to the employment of the form of toothed wheels shown to the exclusion of other adjustable spacing and retaining mechanism for producing the same effect, but reserve the right to make such changes as fairly come within the scope of my invention.

Having thus described my invention, what I claim as new and desire to secure by Letters Patent is:

1. In a computing machine or the like, the combination with the carriage thereof, of tabulating mechanism arranged to temporarily check the movement of said carriage and yieldingly maintain the same in position for alinement of columns of figures. 105

2. In a computing machine and the like, the combination with the carriage thereof of tabulating mechanism comprising a series of variable retaining devices, a rack movable relatively to the tabulating mechanism and serving to measure the travel and stop the carriage in fixed position when engaged with said tabulating mechanism, and means whereby any one of said retaining devices may be engaged with the rack to align columns of figures, substantially as described. 110

3. In a computing machine and the like, the combination with the carriage thereof, of tabulating mechanism comprising a rotatable disk and a series of toothed wheels having variable delay surfaces pivoted thereto, a rack movable relatively to said tabulating mechanism, and means for rotating the disk to bring the delay surface of any given wheel upon the teeth of the rack to retain it and align columns of figures, substantially as described. 120

4. In a computing machine and the like, the combination with the carriage thereof, of tabulating mechanism comprising a rotatable peripherally notched disk with spacing and retaining members corresponding in number to the notches, pivoted thereto and having variable delay surfaces, a latch engaging with the notches of the disk, a rack moving relatively to said tabulating mechanism, means for rotating the disk to bring either of the spacing members into engagement with the rack to hold the carriage and align columns of figures and regulate the position of figures in each entry in said columns, substantially as described. 135

5. In a computing machine and the like, the combination with the carriage thereof, of tabulating mechanism comprising a rotatable peripherally notched disk with spacing and retaining members corresponding in numbers to the notches, pivoted thereto and having variable delay surfaces, a latch engaging with the notches of the disk, a frame for sustaining said disk and latch, a rack moving relatively to said tabulating mechanism, means for pressing said frame resiliently towards the work, means for 5 rotating the disk to bring either of the spacing members into engagement with the rack to hold the carriage and aline columns of figures and regulate the position of figures in each entry in said columns.
6. In a computing machine and the like, the combination with the carriage thereof, of tabulating mechanism comprising a rotatable peripherally notched disk, a latch engaging with the notches of said disk, a series of toothed wheels pivoted thereto and having delay surfaces of varying extent and means for bringing either of the toothed 0 wheels into engagement with the rack, for the purpose set forth.
7. The combination in the tabulating mechanism of the rotatable notched disk, the variable toothed wheels pivoted thereto, means for rotating said disk, the fixed disk having 5 a finger piece, the elbow lever having a thumb piece coöperating with said finger piece and the elbow latch lever pressed into engagement with the notches of the rotatable disk by a spring and thrown out by the action of the first named lever, substantially as described.
- 0 8. In a computing machine or the like, tabulating mechanism comprising a rotatable spacing member, in combination with a coöperating rack bar therefor the two being yieldingly engaged; one of said parts being permanently secured to the frame of the machine and the other longitudinally movable in relation thereto, whereby the stepping member may be engaged with the rack at any point in its length and operate to regularly space in either direction therefrom.
9. In a device of the kind described, rotatable retaining mechanism provided with delay surfaces, and a rack bar adapted to coöperate with said mechanism, one of said 5 parts being permanently secured to the frame of the machine and the other longitudinally movable in relation thereto.
10. In a device of the kind described, the combination with a carriage, of tabulating mechanism, a rack movable relatively to said tabulating mechanism, means to engage the tabulating mechanism with said rack to check the movement of said carriage in either direction at certain points and means for changing the position of said points. 45
11. In a device of the kind described, the combination with a carriage of tabulating mechanism, a rack relatively movable to said tabulating mechanism, means to engage said tabulating mechanism with said rack to check the movement of said carriage in either direction at certain 50 points, and means for changing the position and distance between said points.
12. In a device of the kind described, a rack bar, a tabulating mechanism comprising a plurality of mutilated gears, any one of which may be brought into engagement with said rack bar, the normal portion of each gear being of different length and provided with teeth adapted to mesh with the teeth upon said rack bar. 60
13. In a device of the kind described, a rack bar, a tabulating mechanism comprising a plurality of mutilated gears, any one of which may be brought into engagement with said rack bar, the normal portion of each gear being of different length and provided with teeth arranged to engage the teeth of said rack bar in any position of said gear. 65
14. In a device of the kind described, a rack bar, a mutilated gear, means for bringing said gear into engagement with said rack bar, the normal portion of said gear having teeth adapted to mesh with the teeth upon said rack bar and arranged to engage the same in any position of the gear. 70
- In testimony whereof, I have hereunto signed my name in the presence of two (2) subscribing witnesses.
